United States Patent Office

Des. 201,849
Patented Aug. 3, 1965

201,849

CAN END

Dwight B. Smith, Laguna Beach, Calif., assignor to
National Can Corporation, Chicago, Ill., a corpora-
tion of Delaware

Filed Jan. 12, 1965, Ser. No. 83,397

Term of patent 14 years

(Cl. D58—26)

FIG. 1 is a top plan view of a can end showing my new design;

FIG. 2 is a side elevational view of the can end of FIG. 1;

FIG. 3 is a bottom plan view of the can end of FIG. 1;

FIG. 4 is a cross-sectional view thereof taken on line 4—4 of FIG. 1 on an enlarged scale.

The dotted line showing of the can in FIG. 4 is for illustrative purposes only.

I claim:

The ornamental design for a can end, substantially as shown and described.
